PENCIL SHARPENER

Glen E. Wimmer, Chicago, Ill.

Application January 7, 1947, Serial No. 720,642

2 Claims. (Cl. 120—96)

1

This invention relates to improvements in sharpeners, such as pencil sharpeners.

An object and an advantage of my invention is the provision of a pencil sharpener of the type where rotary sharpening elements are provided at an acute angle to each other, and adapted in one form to rotate in opposite directions whenever a hand plunger is moved downwardly or inwardly to cut on the downward or inward stroke, and to return on the upward or outward stroke without cutting.

In the second form, I have provided similar cutters which cut on both strokes. In each case, the plunger which is pressed downwardly is retracted by a spring.

The foregoing is accomplished by means of clutch mechanism devised by me.

In the first form, when I depress the plunger, a rack will turn a pinion which will operate a clutch disc of a clutch. This clutch may be of a ball or pawl or other type, as will hereinafter more fully appear.

As the clutch disc is turned by the pinion, by operation of the plunger on the downward stroke, the disc will engage the clutch housing, thereby causing the cutters to turn and sharpen the pencil.

On the return stroke, the spring will retract the plunger and revolve the clutch disc in the opposite direction to disengage the clutch housing.

In the ball type clutch, the ball will be moved to one side, to disengage the clutch, allowing the plunger to be retracted without causing the cutters to turn.

In the second form, the plunger may be depressed by the hand, as before, causing the rack, which may be integral with the plunger, to operate the pinion, to operate the clutch disc, as before, with similar action. At this time the second or reversed clutch disc will be disengaged.

At the beginning of the upward stroke, the disengaging action is similar to that described above, to wit: the spring will retract the plunger, and the ball or pawl will operate to disengage the housing. The rack will again operate the pinion, the disc and an intermediate set of gears, to operate the reverse clutch disc in the reverse direction. This again engages the clutch housing to rotate the cutters in the same direction as on the downward stroke.

Other objects of my invention will be apparent from the following specification describing my invention and from the accompanying drawings forming a part of said specification, wherein, merely for the purpose of illustration, several spe-

2

cific, but non-limitative embodiments of my invention are shown.

In the drawings:

5 Figure 1 is a vertical longitudinal sectional view taken through an embodiment of my invention actuated by a vertically moving plunger showing said plunger in depressed position.

Figure 2 is a sectional view taken on line 2—2 of Figure 1.

10 Figure 3 is an elevational side view of the embodiment illustrated in Figures 1 and 2, showing the plunger in raised position.

Figure 4 is a sectional view taken on line 4—4 in Figure 1, with a portion of the casing of the overrunning ball clutch cut away.

Figure 5 is a similar section showing an optional ratchet and pawl overrunning clutch.

20 Figure 6 is an elevational side view of the pencil sharpener according to my invention, wherein the actuating plunger is replaced by a crank lever and a sector gear.

25 Figure 7 is an elevational side view of another embodiment of my invention actuated by a vertically sliding plunger and equipped with two overrunning clutches operating in opposite directions, and provided with the necessary gear transmissions.

Figure 8 is a sectional view taken on line 8—8 in Figure 7.

30 Figure 9 is a sectional view taken on line 9—9 in Figure 7.

Figure 10 is a top plan view of an arrangement similar to Figure 6, the crank lever being replaced by a straight lever arm and the sharpener housing being provided with a rigid handle.

35 Figure 11 is an elevational side view of Figure 10, and

Figure 12 is an elevational side view showing a lever arm engaging a vertically slid able rack as 40 actuating means for the rotary sharpeners.

Referring now in detail to the drawings and first to the plunger-actuated embodiment of my invention shown in Figures 1 to 3, which is generally designated 7, the device comprises a vertically elongated casing 8 having a substantially rectangular cross-section and a semi-cylindrical upper portion 9, in which a multiple cutter rotary pencil sharpener unit 10 of any preferred conventional form is arranged coaxially with this upper casing portion 9.

45 A hollow stub shaft 11, forming a part of the unit 10, terminates in a flat cylindrical overrunning clutch housing 12.

50 As indicated in Figure 1 the cutter rollers or knives 14, forming also a part of the sharpener

unit 10, are arranged at an acute angle relatively to each other, so that a pencil (not shown) can be inserted between them through a tubular opening 15 in the front wall of the casing 8. The front ends of the rollers 14 are rotatably supported by a bridge 16, and the rear ends thereof by a bracket, from which the hollow stub shaft 11 extends rearwardly.

A clutch disc 17, is rotatably supported in the clutch housing 12, and has a solid stub shaft 18 which is rotatably arranged in a boss 19 on the rear wall 13 of the casing 8.

In the overrunning clutch form shown in Figures 1 and 4 the clutch disc 17 has in its circumference a rectangular notch 20, in which is positioned a clutch ball or roller 21. An expanding helical spring 22, seated in a socket 23, urges the clutch ball or roller 21 toward the smaller end of the chamber defined by the corresponding wall of the notch 20 and the inner side of the rim 24 of the clutch housing 12.

On the solid stub shaft 18 a pinion 25 is rigidly mounted and is located between the boss 19 and the clutch housing 12. A rack 26 on a plate-like vertically elongated plunger 27 engages the pinion 25. The plunger is slidably arranged in a guideway 28 formed on the rear wall 13 of the casing 8. The plunger 27 has on its upper end a forwardly extending convex handle 29 projecting over the top of the housing 8.

A helical tension spring 30 is fastened with one of its ends on a lug 31 on the lower end of the plunger 27, and with its other end on a lug on the top 9 of the casing 8. The spring 30 urges the plunger 27 upwardly into the raised position shown in Figure 3. Whenever the plunger 27 is pushed downwardly the clutch disc 17 is turned in the operative running direction, thereby causing the rotary sharpening assembly 10 to sharpen a pencil (not shown) which is inserted between the cutter rollers 14. At the same time tension is stored in the spring 30. When the plunger is released the spring 30 forces the plunger 27 upwardly, thereby turning the clutch disc 17 in inoperative direction.

A partition 32, having an opening 33 accommodating the rotary cutter unit 10, is provided to protect the plunger 27 and clutch mechanism from pencil shavings, and to define beneath the cutter assembly 10 a compartment 34 adapted to receive a shavings receptacle 35, which can be easily removed and replaced through the open bottom 36 of the casing 8.

The overrunning clutch mechanism described above may be omitted or some other form thereof may be substituted, for instance such as the ratchet and pawl type illustrated in Figure 5, wherein the rim 24a of the clutch housing 12a is provided with ratchet teeth, and the clutch disc 17a has a pawl 37 pivoted on its circumference, which is urged by a spring 38 into constant engagement with the ratchet teeth.

Figure 6 illustrates another embodiment, in which the plunger 27 and the guideway 28 is omitted. The plunger 27 is replaced by a crank-lever 27a rotatably attached on one side of the rear wall 13a of the casing 8a and has a handle 29a on its outer end. A sector gear 26a is connected with the crank-lever 27a and engages a spur gear 25a rigidly mounted on the solid stub shaft 18a. On the inner end of the crank-lever 27a a hooklike member 40 is provided and is located below the pivot 39 of the crank-lever. A helical spring 41 is attached with one of its ends to this hooklike member 40, and with the

other end at 42 to the rear wall of the casing 8a.

By rotating the crank-lever 27a toward the left the sharpener unit 10 will be operated, and tension will be stored in the spring 41. This tension will return the lever 27a into its original position.

In this embodiment also the overrunning clutch mechanism may be omitted or any of several different forms thereof can be employed for instance such as those illustrated in Figures 4 and 5.

In the Figures 7, 8 and 9 another modification of the pencil sharpener according to my invention is illustrated, and the object of this modification is to provide a pencil sharpener of the class described adapted to sharpen a pencil not only when the actuating plunger is forced downwardly but also during the upward movement of said plunger.

In general the pencil sharpener according to this modification is constructed like the pencil sharpener described above. It has a casing 8a provided with a semi-cylindrical upper portion 9a, in which a multiple cutter rotary pencil sharpener unit 10a of any preferred conventional form is arranged coaxially with this upper casing portion 9a. The cutters 14a of the pencil sharpener unit 10a are rotatably supported at their front ends by a bridge 16a and at their rear ends by a bracket 17a. A vertically extending partition 32a, having an opening 33a therein to accommodate the rotary cutter unit 10a, is provided to protect the mechanism to be described later from pencil shavings and the like, and to define beneath the cutter assembly 10a a compartment 34a adapted to receive a shavings receptacle 35a, which rests slidably on the bottom of the casing 8a and can easily be removed through an opening provided therefor in the front wall of the casing.

On the bracket 17a a solid rearwardly extending shaft 43 is formed and is rotatably supported in an outwardly extending bearing boss 44. Adjacent the inner surface of the rear wall of the casing 8a a comparatively wide pinion 45 is rigidly mounted on a sleeve 45a, which is rotatably mounted on the solid shaft 43.

A platelike plunger 46 is slidably arranged in guideways 47 formed on the inside surface of the back wall of the casing and has a longitudinally extending, centrally located slot 48 therein, one lip whereof is formed into a rack 49 engaging the pinion 45, which is positioned in the slot 48.

The pinion 45 meshes with a gear 50, which is rotatably mounted on a shaft pin 51, firmly embedded in the rear wall of the casing 8a and a boss 52 formed on the inner surface of this wall.

Rearwardly of the partition 32a the right hand side wall of the housing 8a is curved outwardly, forming an arcuate gear housing 53; the rear wall whereof is formed by a lug 54 extending inwardly from the rear portion of the right hand side wall of the casing 8a. In this lug a short shaft 55 is rotatably arranged, and on the rear end of this shaft another spur gear 56 is rigidly mounted meshing with the above mentioned gear 50. On the forward end of the short shaft 55 a third gear 57 is rigidly mounted meshing with a fourth gear 58 rotatably mounted on the solid shaft 43 adjacent the bracket 17a.

A clutch disk 59, located inside a clutch drum 60 is rotatably mounted on the solid shaft 43 and securely connected to the fourth gear by pins 61. The drum 60 is rigidly connected to the solid shaft 43 by a pin 62 extending diametrically through the shaft 43 and the drum 60.

The clutch disk 59 and the clutch drum 60 form

together an overrunning clutch, which rotates the sharpener unit 10a when the train of gears described above is actuated by the movement of the rack 49 in one direction, but does not influence the sharpener unit, when the train of gears is driven by the return movement of the rack 49.

Rearwardly of the first mentioned clutch disk 59 a second clutch disk 63 is rigidly mounted on the sleeve 45a inside the clutch drum 60, with which it forms a second overrunning clutch operating in the opposite direction to the first described overrunning clutch, so that the sharpener unit 10a is actuated also by the return movement of the plunger 46, which has on its upper end a forwardly extending convex handle 64 projecting over the top of the casing 8a.

A helical tension spring 65 is fastened with its upper end onto a lug 66 on the inside of the top of the casing 8a and with its lower end to a pin 67 in the lower portion of the plunger 46. The plunger is forced downwardly by hand actuating the sharpener unit 10a to rotate in one direction and simultaneously storing tension in the helical spring 65, which will return the plunger upwardly, when the hand is removed from the handle 64, thereby actuating the sharpener unit.

In Figures 10 and 11 a modified pencil sharpener is illustrated having a casing 68 in which a multiple rotary sharpener unit (not shown) is arranged, being rigidly mounted on a shaft 69 rotatably mounted in the rear wall of the housing 68. There is a tubular entry 10 on the front wall of the casing 68 to permit a pencil (not shown) to be inserted. A pinion 71 is rigidly mounted on the shaft 69. A handle 72 is integrally formed with or firmly fastened to the left hand side of the casing 68. A sector gear 73 is rigidly mounted on a shaft 74 rotatably arranged in the rear wall of the casing 68. On the same shaft a downwardly and leftwardly extending lever arm 75 and a downwardly extending hook lever 76 are rigidly mounted. A helical tension spring 77 is attached with one of its ends to a pin 78 on the rear wall of the casing 68 and with the other end to the hook lever 76 normally urging the hand lever 75 in the downwardly and leftwardly inclined position. The pencil sharpener is actuated by compressing the handle 72 and the lever arm 75 and the spring 77 will return the sharpener into starting position.

In Figure 12 another modification of the pencil sharpener according to my invention is illustrated. Here the casing 79 is also provided on its left side with a handle 80 and a lever arm 81 is rigidly mounted on a shaft 82, which is rotatably supported in the rear wall of the casing 79.

Inside the casing a pencil sharpener unit is arranged and rotatably supported as described for Figures 1 and 2 and the solid shaft on the clutch disk has a pinion 83 rigidly mounted thereon, which is in mesh with a short rack 84 formed on a slide 85 slidably mounted in guideways 86 on the inside surface of the rear wall of the casing 79. The lever arm 81 has a pin or the like extending through slot in said rear wall and engaging the slide 85, so that reciprocal pivotal movement of said lever arm is translated to up and down movement of the slide and reciprocal rotary movement of the pinion 83 and the sharpener unit. To return the actuating lever arm 81 into its starting position shown in Figure 12 a hook lever 87 is rigidly mounted on the shaft 82 and extends downwardly therefrom. A helical tension spring 88 is fastened to the hook lever 87 and a pin 89 on the rear wall of the casing 79

and returns the lever arm 81 into its starting position shown in Figure 12.

Having thus described the invention, what is claimed is:

5. A pencil sharpener, comprising an upstanding casing including spaced opposed vertical sides having aligned openings forming bearings, said bearings being arranged near and below the top of the casing and having their axes arranged horizontally, a vertical track arranged adjacent to one of said vertical sides and spaced inwardly thereof to form a narrow vertical passage, said track and passage extending substantially at right angles to the axes of the bearings, a rotary cutter unit mounted horizontally within the casing between the opposed vertical sides and near the top of the casing, the cutter unit having a tubular end shaft journaled within the bearing remote from the passage and adapted to 10 receive the pencil, a clutch housing secured to the inner end of the rotary cutter unit, a shaft journaled within the bearing adjacent to the passage, a clutch disc secured to the last-named shaft for rotation therewith and engaging within 15 the clutch housing, one-way clutch-engaging means operatively connecting the clutch housing and disc, a gear mounted upon the shaft carrying the clutch disc and arranged within the vertical passage, a vertical reciprocating rack bar disposed within the passage and having teeth engaging the gear for driving the cutter unit, the rack bar including a handle extending exteriorly of the housing and above the top of the same, and a spring arranged within the housing and 20 connected with the rack bar and with the housing and serving to bias the rack bar upwardly.
2. A pencil sharpener, comprising an upstanding casing having its bottom open and including spaced opposed vertical sides having aligned 25 openings forming bearings, said bearings being arranged near and below the top of the casing and having their axes arranged horizontally, a vertical track arranged within the casing adjacent to and spaced slightly from one of said vertical sides for forming a narrow vertical passage extending throughout substantially the entire height of the casing, said track and passage extending substantially at right angles to the axes of the bearings, a rotary cutter unit mounted 30 horizontally within the casing between the opposed vertical sides and near and below the top of the casing, the cutter unit having an outer tubular end shaft journaled within the bearing remote from the vertical passage and adapted to 35 receive the pencil therein, an axially-narrow clutch housing secured to the inner end of the rotary cutter unit, a shaft journaled within the bearing adjacent to the vertical passage, a clutch disc secured to the last-named shaft for rotation 40 therewith and engaging within the clutch housing, one-way clutch-engaging means operatively connecting the clutch housing and disc, a gear mounted upon the shaft carrying the disc and arranged within the vertical passage, a vertical, 45 reciprocating rack bar mounted within the vertical passage and engaging the track to be guided thereby, the rack bar having teeth engaging the gear for driving the cutter unit, the rack bar including a handle arranged exteriorly of the housing and above the top therof, a retractile coil spring arranged within the housing and connected with the rack bar near the bottom of the rack bar and with the top of the housing and serving to bias the rack bar upwardly, and 50 a receptacle removably mounted within the cas- 75

ing below the cutter unit and having its top open, the receptacle being insertable and removable through the open bottom of the casing.

GLEN E. WIMMER.
